UNITED STATES PATENT OFFICE

WILLIAM A. JONES, OF WEST NEW BRIGHTON, NEW YORK, ASSIGNOR TO THE BAB-COCK & WILCOX COMPANY, OF BAYONNE, NEW JERSEY, A CORPORATION OF NEW JERSEY

BOILER DOOR

Original application filed July 12, 1923, Serial No. 651,021. Divided and this application filed January 10, 1928. Serial No. 245,650.

This application is a division of my co-pending application, Ser. No. 651,021, filed July 12, 1923.

This invention relates to a novel and improved arrangement of boiler doors and will be best understood from the following description and the accompanying drawings, in which I have shown a selected embodiment of my invention and in which:

10 Fig. 1 is a front view of a portion of a boiler, showing a plurality of doors arranged according to my invention.

Fig. 2 is a section on the line 2—2 of Fig. 1.

Fig. 3 is a view showing how a platform 15 may be temporarily supported on a door.

Fig. 4 is a section taken on the line 4—4 of Fig. 5.

Fig. 5 is a view taken on the lines 5—5 of Figs. 4 and 6.

20 Fig. 6 is a section on the line 6—6 of Fig. 5.

Fig. 7 is a section on the line 7—7 of Fig. 1.

Referring now to the drawings in detail, I 25 have shown the invention as used in connection with a boiler, a part of which is shown in Fig. 2, which comprises vertical water chambers 1 and 2, which are connected to banks of tubes 3 and 4. The tubes are shown 30 as being horizontally inclined and the space in front of the water chambers is closed by a plurality of doors 5. When it is necessary to clean or remove tubes, or make any other repairs to the boiler, it is desirable to remove one or more doors and to facilitate this 35 removal and the subsequent replacement, I have devised the arrangement forming the subject matter of this application.

Extending transversely of the boiler and 40 in front of the water chambers, is a lintel 6, upon which each door is hung by means of a plurality of hooks 7. Disposed in front of the lintel 6 is a track here shown as an I-beam 8, upon which runs a hoist 9 having a hook 10 45 which is adapted to engage an attaching member 11 upon each door. Each door is secured in position by suitable clamps 12 which are mounted upon vertical side pieces 13, and which may be manually operated.

50 It will be noted that each hook 7 is so ar-

ranged with respect to the lintel 6 which it engages, that a limited amount of horizontal movement of the door with respect to the lintel is permitted.

In Figs. 1 and 2, I have shown one door 5' 55 as in the condition of being removed or replaced and it will be seen that a lifting of the door by the hoist after the clamps have been unfastened, will remove the door and cause it to swing outwardly away from the 60 boiler. On the other hand, if it is desired, the hooks 7 may be left in engagement with the lintel and the door may be swung outwardly to the full line position shown in Fig. 3. The normal position of the door is 65 shown in dot and dash lines in this figure. When the door has been thus swung outwardly, a suitable platform 14 may be placed between the door and the boiler, resting upon the angle iron 15 at the bottom of the door 70 and upon the horizontal sill 16. The platform is then in position to be occupied by workmen engaged in repairs or other work on the boiler.

The angle iron 15 preferably extends completely across the bottom of the door and finds its counterparts in other angle irons 15 disposed adjacent other edges of the door. Between the lintel 6 and the upper edge of the door, is disposed a suitable packing material 17 which is compressed and thus seals the joint between the lintel and the door, when the door is in position. Similar packing material is disposed between each edge of the door and adjacent supporting members such as the vertical members 13 and the horizontal member 16. 85

By the arrangement shown, not only are the doors made tight against the frame of the opening so as to prevent the passage of 90 gas from the boiler to the exterior or the leakage of air into the boiler, but the space between the water chambers and the casing is also closed so as to prevent the short-circuiting of gases through this space, it 95 being noted that the lintel, sill, and vertical members are all sealed to the boiler.

It will be obvious that the doors may be inclined somewhat to the vertical without departing from my invention and in the ap- 100

pended claims, when I have described the doors as substantially vertical, it will be understood that the term includes any arrangement in which the doors are either strictly vertical or inclined to the vertical.

It will be understood that the arrangement described is merely illustrative and that the application of my embodiment may be widely varied.

10 I claim:

1. In a boiler casing, a substantially vertical door adapted to cover an opening in the casing, a lintel above the opening, hooks on the top of the door to engage the lintel to support the door and having limited horizontal movement thereon away from the casing, and clamps around the edges of the door to hold the same in contact with the frame of the opening.

20 2. In a boiler casing, a substantially vertical door adapted to cover an opening in the casing, a lintel above the opening, hooks on the top of the door to engage the lintel to support the door and having limited horizontal movement thereon away from the casing, packing between the edges of the door and the frame of the opening and clamps around the edges of the door to hold and compress the packing between the door and the frame.

30 3. In a boiler casing, a substantially vertical door adapted to cover an opening in the casing, a lintel above the opening, hooks on the top of the door to engage the lintel to support the door and having limited horizontal movement thereon away from the casing, and clamps around the edges of the door to hold the same in contact with the frame of the opening, the face of the door being substantially vertical when the door is supported on the hooks alone.

40 4. In a casing for a water tube boiler having horizontally inclined tubes and water chambers at either end thereof, a lintel and a sill parallel thereto, vertical side pieces extending from the sill to the lintel to form therewith the frame of an opening with the outer edge of the frame spaced outwardly from the water chamber, the lintel and the sill being sealed to the water chamber, and doors over said opening and sealed to the frame thereof, whereby a sealed space is formed between the water chamber and the doors.

50 5. In a boiler casing, a substantially vertical door adapted to cover an opening in the casing, a lintel above the opening, pivotal connections between the top of the door and the lintel to support the door, said connections being arranged to permit the bottom of the door to be swung away from the sill and the door and the sill being arranged to support a platform inserted between the bottom of the door and the sill to hold the door in its outer position.

6. In a boiler casing, a frame providing an opening, a door to cover and seal said opening, said frame including a lintel and a sill, pivotal connections between the top of the door and the lintel to support said door from said lintel and position the door rotatably about the lintel, and a ledge on the door to cooperate with the sill to support a platform between the door and the frame, whereby the door may be held in spaced position relative to the frame.

WILLIAM A. JONES.
